UNITED STATES PATENT OFFICE.

MATHEW E. ROTHBERG, OF LEBANON, PENNSYLVANIA.

COKE-OVEN.

SPECIFICATION forming part of Letters Patent No. 720,971, dated February 17, 1903.

Application filed May 14, 1902. Serial No. 107,355. (No model.)

To all whom it may concern:

Be it known that I, MATHEW E. ROTHBERG, a citizen of the United States, and a resident of Lebanon, in the county of Lebanon and State of Pennsylvania, have made a certain new and useful Invention in Coke-Ovens; and I declare the following to be a full, clear, and exact description of the same, such as will enable others skilled in the art to which it appertains to make and use the invention, reference being had to the accompanying drawings, and to letters of reference marked thereon, which form a part of this specification.

The invention relates to coke-ovens; and it consists in the novel construction and combinations of parts, as hereinafter set forth.

The object of the invention is to provide, in connection with horizontal open-end coke-ovens having a system of heating or combustion flues between and underneath the coking-chambers, means for efficiently regulating and distributing the heat in the different flues, thereby affording means for heating the different parts of the oven-wall at will, for recovering the heat from the waste gases to the air-supply, and for utilizing the dead heat in the top of the flues for heating the air before it enters into the combustion-flues, whereby it is designed to secure great heat economy, strength of construction, and rapidity of coking action.

The nature of this improvement will be best understood in connection with the drawings illustrating the same, in which—

Figure 1 is a longitudinal section through a main system of heating and combustion flues, the section being taken on the line H H, Figs. 3 and 4. Fig. 2 is a longitudinal section taken on the line J J, Fig. 3. Fig. 3 shows vertical sectional views taken on the lines A A, B B, and C C, Fig. 1, and also shows an end view of oven and flue. Fig. 4 shows sections taken on the lines E E, F F, and G G, Fig. 1, as well as a top view of the oven and flue. Figs. 5 and 6 are detail sectional views illustrating the valves f and adjacent parts.

The letter A' indicates a suitable foundation for the ovens B', this foundation containing a series of passages H', serving, respectively, as cooling-flues for the ovens above them.

The ovens are built in adjacent pairs, as

indicated, and the interval or wall in the structure between the coking-chambers is hollow, its chamber portion or cavity being divided into two compartments by a transverse vertical wall D'. Each of these compartments is traversed by a vertical series of longitudinal horizontal combustion or heating flues B³, formed by deflecting-partitions b, one above another, having, respectively, alternate openings at their front and inner ends, such flues communicating at their ends and the series communicating below with a series of short connected transverse horizontal flues C', the latter flues extending under the oven-chamber. The lower flue B³ communicates with flues C' by means of angular flues or passages B⁴. The flues C' are formed by short transverse deflecting-partitions c. To the uppermost of the series of flues B³ extends a pipe H³ from the fuel-gas main G², and the heated gases pass through the flues B³, B⁴, and C' to the flue C² in the foundation, wherefrom they pass out by means of a suitable stack. In the draft-flue C² is located an air-pipe D², in which air is heated by the waste gases passing to the stack, and this heated air is conveyed to the main air-pipe D³, which communicates with hot-air flues F³, formed in the structure above the level of the tops of the ovens, by means of a pipe F⁶, which is provided with a regulating-valve E². The pipe H³ from the fuel-gas main is also provided with a regulating-valve G³. The flue F³ is provided with a longitudinal deflecting-partition a, whereby the heated air is caused to traverse the structure back and forth to the passage to flue B³. Connection can be made to the gas-main G² by passage, pipe, or flue E³, and the gas can be conveyed from pipe E³ to flues B³ by means of pipes E⁴, having regulating-dampers. Provision is also made for supplying the flues B³ with cold air by means of pipes E⁵ E⁶, having regulating-dampers. The products of combustion can be made to pass directly from each flue B³ to the next flue B³ without traversing the length of the flue by means of short-circuiting passages F⁴. The passages F⁴ are arranged in series under the pipe or flue H³ and in line with each other and are provided, respectively, with valves f, which can be opened or closed at will by removing

plugs f' in the wall of the furnace to cut out one or more of the flues B^3 , so that the heating may be changed from any part of the oven-wall to any other part thereof at will.

5 These plugs close openings in the wall of the furnace, an opening being located adjacent to each such valve. By means of these combustion-flues and air-flues the oven-chambers are encompassed in such wise that their heating can be quickly accomplished and easily regulated to suit the work. The flues F^3 in the top of the structure serve to recover the dead heat and provide for its utilization in the air-supply.

15 Having thus described my invention, what I claim as new, and desire to secure by Letters Patent, is—

1. In adjacent open-end coking-ovens, a hollow longitudinal wall separating the oven-chambers, longitudinal deflecting-partitions forming reverting combustion-flues in the cavity or chamber of said wall, alternate partitions having openings therethrough forming short-circuiting passages connecting said flues, and provided with sliding valves, the oven-wall having an opening adjacent to each such valve, and plugs for closing such openings, substantially as specified.

2. In adjacent coking-ovens, having the draft-flue provided with a hot-air pipe therein, a hollow longitudinal wall separating the oven-chambers, longitudinal deflecting partitions forming reverting combustion-flues in the cavity or chamber of said wall, alternate

partitions having openings therethrough 35 forming short-circuiting passages connecting said flues and provided with sliding valves, the oven-wall having an opening adjacent to each such valve and plugs for closing said openings, said ovens having each a chamber 40 thereunder provided with transverse partitions forming communicating flues leading to the draft-flue, and connecting with said combustion-flues, said ovens having also air-flues above the oven-chambers communicating 45 with said combustion-flues, and with said hot-air pipe, substantially as specified.

3. In adjacent open-end coking-ovens, a hollow longitudinal wall separating the oven-chambers, a series of longitudinal deflecting- 50 partitions having respectively openings at alternate front and inner ends and forming a vertical series of horizontal reverting combustion-flues in the cavity or chamber of said wall, a fuel-pipe leading thereto, openings arranged in series in alternate partitions and in line with each other, and forming short-circuiting passages connecting said combustion-flues and provided respectively with sliding cut-out valves, whereby the action of the 55 combustion-flues is locally adjustable, substantially as specified.

In testimony whereof I affix my signature in presence of two witnesses.

MATHEW E. ROTHBERG.
